ATTORNEY

UNITED STATES PATENT OFFICE

151,201

DESIGN FOR A RACK POOL BOARD

Harvey M. Wescott, South Westport, Mass.

Application September 18, 1946, Serial No. 133,392

Term of patent 14 years

(Cl. D34—5)

To all whom it may concern:

Be it known that I, Harvey M. Wescott, a citizen of the United States, residing at South Westport, in the county of Bristol, in the State of Massachusetts, have invented a new, original, and ornamental Design for a Rack Pool Board, of which the following is a specification, reference being had to the accompanying drawing, forming a part hereof.

I claim:

The ornamental design for a rack pool board, as shown.

HARVEY M. WESCOTT.
